UNITED STATES PATENT OFFICE

EDWIN H. HELLER, OF SIKESTON, MISSOURI

SHOE VENTILATING DEVICE

Application filed August 12, 1931. Serial No. 556,671.

My present invention has reference to a new and novel construction of shoes, and my object is the provision of a shoe having an insole or inner sole construction of such character as to afford elasticity to the foot of the wearer and likewise force continuous blasts of air against the wearer's foot as long as he is walking.

To the attainment of the foregoing the invention consists in the improvement herein-
10 after described and definitely claimed.

In the drawing:

Figure 1 is a side elevation of the improvement, with parts in section of a shoe constructed in accordance with this invention.

15 Figure 2 is a plan view of the inner sole.

Figure 3 is a plan view of the main sole with the inner sole or lining removed.

Figure 4 is a detailed perspective view looking toward the rear of the metal heel plate.

20 The shoe is indicated in the drawing by the numeral 1, the main sole by the numeral 2 and the heel by the numeral 3. The outer edges of the main sole 2 have stitched on the edges and ends thereof a continuous leather strip 4.

25 Thus the main sole 2 has its top formed with a depression which affords an air chamber or pocket. The upper of the shoe is stitched to the leather strip or flange 4 and received in the air pocket in the main sole 2 and secured therein in any desired or preferred manner

30 there is a leather sheet or strip 5. The portion of this sheet extending beyond the arch of the shoe and over the sole proper is centrally slitted or divided to receive therein a thin metal plate 6.

35 By slitting the sheet, at the sole portion thereof, and arranging the metal plate 6 therein the coiled expansion springs (hereinafter to be described) will embed themselves in the upper slitted portion of the sheet 5 and will thereby be held properly positioned.

The insole 8 rests on the flange 4 and is stitched thereto, as at 8'. The inner sole is of leather and as disclosed by the drawing has both its body or sole portion as well as its heel portion provided with series of both longitudinally and transversely arranged apertures 9 that afford air passages. For distinction the sole portion of the inner sole is indicated by the numeral 10, the arch by

the numeral 11 and the heel portion by the numeral 12. Arranged under the sole portion 10, and disposed directly over the sole portion of the air pocket or chamber there is a metal plate 13 provided with apertures 14 which are in register with the apertures 9. Secured to the outer face of the thin but strong metal plate 13 there is a plurality of short helical springs 15, the outer ends of said springs bear against the upper face of the split sole portion of the leather member 5 and exerting pressure against the metal reinforcing plate therein. This, as previously stated, will hold the springs 15 properly positioned. The inner end of the plate 13 has centrally fixed thereto by rivets or like elements an arched metal shank 15' which is arranged beneath the arch 11 of the insole 8. The metal shank 15' is arched so that the same will overlie and have its free end connected to a thin metal plate 16 which is arranged over the heel portion of the leather member 5. The heel portion 12 of the insole has secured on its inner face a metal plate 17 which is provided with apertures 70 that register with the apertures in the said heel portion of the shoe. The plate is, of course, shaped to correspond in shape to the heel portion 12 of the insole and likewise the heel portion of the main sole of the shoe. The plate 17 has fixedly secured on its inner face a plurality of short helical springs 18 which are in contact with the metal plate 16. The outer rounded edge of the plate 17 is provided with a flange 19 that has spaced notches 20 to afford air ports or passages, and the rounded edge of the heel portion 12 of the insole is notched to provide the same with an arcuate slot 21 disposed opposite certain of the notches 20 of the flange 19. The notches 20, and 21 afford air passages for the rear of the shoe 1.

The plate 17, and the plate 13 are of thin but strong metal while the shank plate 16 is of stiff metal. The flanges 19 (which are of a less length than the normally expanded springs 18), when brought against the plate 16, by the weight of the user of the shoe, limits the compression of the springs 18, and consequently the movement of the heel plate 104

17 in the direction of the heel of the shoe. The sole and shank portion of the insole 8 has its edges stitched to the flange 4 of the main shoe and to the inturned edges of the 5 body of the shoe, so that only the central and reinforced portion of the sole part 8 of the insole is yieldable.

From the foregoing description when read in connection with the accompanying drawing it will be apparent that the improvement 10 effectively cushions the foot of the user of the shoe and that in walking the yieldable sole and heel portions of the inner sole will be depressed when the shoe is brought into 15 ground contacting position and will be expanded when the shoe is lifted off the ground so that the foot of the user is afforded a continuous circulation of air. The improvement is, broadly speaking, in the nature of an air 20 pump and such air is not only distributed to the sole and under face of the heel of the user, but along the sides of the user's foot and especially along the sides of the heel of the user of the shoe. The foot of the user is 25 naturally moved toward the front of the shoe and is not in direct contact with the rear of the shoe, so that the ports or notches 20 and 21 will open to each other and a volume of air will be pumped through these 30 notches. When, however, the foot of the user is set for action, or in other words the user is walking, the foot in the shoe slides toward the back of the shoe, commonly called the counters, and such movement will cover 35 the notch 21 so that an intermittent flow of air is directed through the said notch or opening 21 when the user raises and lowers his foot in ground contacting engagement when walking. The inner sole is of soft leather 40 and effectively cushions the foot of the user of the shoe and it is thought the foregoing description will fully and clearly set forth the simplicity of my construction and the advantages thereof, so that further detailed 45 description will not be required.

It is to be further noted that the improvement provides the shoe with a double air pump, one arranged at the sole and the other at the heel portion of the shoe.

Having described the invention, I claim:
A foot cushioning and ventilating shoe including a sole provided with a continuous upstanding flange that affords the sole with an air pocket, a compressible strip arranged 55 in the pocket and having its sole portion centrally slotted, a metal reinforcing plate in the slit, a thin metal plate overlying the strip at the heel portion thereof, a stiff metal shank secured to the arch of the strip and to the 60 metal heel plate, an apertured metal plate to which the front end of the shank is secured, coiled expansion springs between said apertured metal plate and the sole portion of the compressible strip, an apertured plate at 65 the heel portion of the pocket having its

rounded rear portion provided with a depending flange which is notched, coiled compression springs on the under face of the said apertured plate of a normal length greater than that of the flange, and a leather inner sole having its front and rear portion apertured, its central portion connected to the metal shank, its edges stitched to the flange of the shoulder and the rounded edge of its heel portion provided with an arcuate notch disposed outwardly of the notched flanges on the apertured heel plate.

In testimony whereof I affix my signature.
EDWIN H. HELLER.
